UNITED STATES PATENT OFFICE

HENRY H. MCPHAUL, OF YUMA, ARIZONA

ARCH SUPPORT

Application filed August 21, 1929. Serial No. 387,432.

The present invention relates to improvements in arch supports, and has for an object to provide an improved arch support that will give improved cushioned support to the arch 5 of the foot, and maintain its place against creeping in the shoe.

Another object of the invention is to provide an improved arch support, in which the heel will be cushioned against shocks and jars, 10 and in which the perspiration of the foot will be absorbed and a comfortable and sanitary condition promoted throughout the shoe.

With the foregoing and other objects in view, the invention will be more fully described hereinafter, and will be more particularly pointed out in the claims appended hereto.

In the drawings, wherein like symbols refer to like or corresponding parts throughout the 20 several views,

Figure 1 is a perspective view with parts broken away of an improved arch support constructed in accordance with the present invention.

Figure 2 is a side view of the same.

Figure 3 is a longitudinal section taken on the line 3—3 of Figure 1.

Figure 4 is a cross section taken on the line 4—4 in Figure 1.

Figure 5 is a similar view taken on the line 5—5 also in Figure 1, and

Figure 6 is a perspective view showing a slightly modified form of the invention.

Referring more particularly to the drawings, 10 designates an insole of the outline and form of a shoe in which the device is to be utilized.

This insole is preferably formed of goat or sheep skin, in which the skin side is indicated at 11 and the wool side at 12. The insole with the skin side down is adapted to be placed in the shoe, so that the wool 12 is presented to the foot. The heel is preferably built up of a cushion of rubber 13 placed upon the wool 40 layer 12 and supporting thereupon a heel piece of skin 14 and wool 15. The rubber 13 is preferably provided with perforations 16 to ventilate the same and permit of the passage therethrough of any moisture which 50 might tend to collect on the rubber. More-

over, the perforations admit the wool 12 and assist the center rubber piece in place. The top heel piece 15 is secured to the rubber and to the insole in any appropriate way, as by the use of stitches secured at the points 17 and 18. It is only necessary to apply these stitches at the forward and rear central portions of the heel, but other fastening means at various other points may be employed if desired.

The arch portion of the device is composed of two pieces of skin 19 and 20. The piece 20 is of substantially the same width or slightly less width than the arch portion of the insole, and it is placed upon the insole preferably with the wool side 21 down.

Appropriate fastening means is employed to hold the piece 20 to the insole, and I have shown the same stitched along its rear edge by three groups of stitching 22, one such group being centrally and the other groups at the corner portions of the strip. In a similar way the forward edge of the piece 20 is secured by groups of stitching 23 to the insole. The intermediate portion of the piece 20 is not initially secured to the insole but an arch strip 19 is first threaded laterally through the space between the insole and the piece 20, and it is so located that its central part lies through the piece or strap 20.

The stitching 24 may then be made through the three thicknesses of material, namely through the insole, the piece or strap 20 and the intermediate portion of the lateral strip 19. Thereafter, the end portions of the lateral strip 19, which project out beyond the strap 20 and the insole are overturned upon one another and upon the strap 20 in the manner indicated in Figure 1. In other words, one end 25 is turned over upon the strap 20 and then the other end 26 is folded over upon the end portion 25. This forms a built up structure at the arch of the foot composed of five layers of skin in addition to the wool adhering to the skin which forms cushions between the laminations of skin and the whole provides a soft, yieldable yet firm support for the internal arch of the foot.

Moreover, the end portions of the strap 20 which extend in front of and in rear of

the arch supports 25 and 26, form stepped-down shoulders for receiving the adjacent under portions of the foot and avoid the creation of any voids immediately before and behind the arch support which would leave the foot unsupported. Stitching 27 and 28 passes through the end portions 25 and 26 at the sides of the arch support, so that they will not be disagreeable to the foot and by so binding the parts of the arch support at only two points, the parts are free to accommodate themselves to the peculiarities of any particular foot.

The rubber pad at the heel, in combination with the woolen sheep skin portions, relieves the body from all jar in walking and minimizes sound in walking over hard surfaces, thus relieving inflammatory nerve conditions, such as neuritis and muscular troubles that would apt to be aggravated by such shocks. The device is adjustable to any particular foot by raising or lowering both the heel rest and the arch support with additional material.

The material employed is durable, flexible and readily cleansed by the simplest processes. It also dries quickly and may be ready for use in a comparatively short time which gives it great advantage over woven fabric of wool or cotton and other like materials which absorb and hold moisture much longer.

The insole may be made independently from the shoe and slipped into same.

With regard to Figure 6, a modified form of the invention is shown in which the insole strip 19', while made of the same material is reversed, so that the skin side is uppermost and presented to the foot while the wool side lies downwardly.

It is obvious that various changes and modifications may be made in the details of construction and design of the above specifically described embodiment of this invention without departing from the spirit thereof, such changes and modifications being restricted only by the scope of the following claims.

What is claimed is:—

1. An improved arch support comprising an insole of animal skin having the wool adhering thereto and presented to the foot, a strap of the same material secured at its forward and rear ends across the instep portion of the insole and forming a lateral pocket, and an arch supporting strip also of the same material threaded through the pocket and having its end portions folded over upon one another and upon the strap and secured together, said arch supporting strip being narrower than the strap is long to provide stepped shoulder portions at opposite sides of the arch support.

2. An improved arch support comprising an insole of animal skin having wool adhering thereto and presented upwardly to the

foot, a strap of similar material placed with the wool side down and being of substantially the same width as the arch portion of the insole and laid thereon, means to secure the forward and rear portions of the strap to the insole leaving a transverse pocket between the intermediate portion of the strap and insole, and an arch supporting strip narrower than the strap is long having its intermediate portion engaged in said pocket and secured therein and said strip having its end portions folded over upon one another in opposite directions and upon the strap and secured to one another at the side portions of the insole.

In testimony whereof I affix my signature.

HENRY H. McPHAUL.
